UNITED STATES PATENT OFFICE.

LUTHER SHERRILL, OF NASHVILLE, TENNESSEE, ASSIGNOR TO MERGENTHALER LINOTYPE COMPANY, A CORPORATION OF NEW YORK.

TYPOGRAPHICAL MACHINE.

1,383,769.

Specification of Letters Patent.

Patented July 5, 1921.

Application filed June 28, 1920. Serial No. 392,207.

To all whom it may concern:

Be it known that I, LUTHER SHERRILL, a citizen of the United States, residing at Nashville, in the county of Davidson and State of Tennessee, have invented certain new and useful Improvements in Typographical Machines, of which the following is a specification, reference being had therein to the accompanying drawing.

10 This invention relates to typographical machines, such as linotype machines of the general organization represented in Letters Patent of the United States to O. Mergenthaler, No. 436,532, wherein circulating matrices are released from a magazine in the order in which their characters are to appear in print and then composed in line in an "assembling elevator," the composed line then transferred through an intermediate 20 channel into a vertically movable "first elevator" which presents it to a mold, whereupon the mold is filled with molten metal to form a slug or linotype against the matrices which produce the type characters thereon, 25 and the matrices thereafter elevated and returned through a distributing mechanism to the magazine from which they started. More particularly, it relates to that class of machines designed to handle matrices provided 30 with two or more superposed characters, and wherein the assembling elevator, intermediate channel, and first elevator are each provided with two sets of supporting rails whereby the matrices may be composed and 35 maintained at an upper or lower level, or both, as desired, to locate the selected characters in operative position.

When it is desired to cast a slug from the lower characters of all of the matrices of a 40 composed line (as for a "solid" line of italics), it is the usual practice to assemble and maintain such matrices, not at the upper level as would otherwise be required, but at the lower level, and then to arrest the first 45 elevator in a slightly raised position so as to locate the selected characters opposite the mold slot, such arrest of the elevator being ordinarily effected by a stop member mounted on the vise frame and adapted to be 50 thrown into action at the will of the operator. Similarly, in the use of "head-letter" matrices or matrices with characters above 14 pt. the same practice is followed so as to effect the proper alinement of the matrix characters 55 with the mold slot. The foregoing practice

has given rise to very serious objections, as it frequently happens that an operator, through oversight or carelessness, will assemble matrices at the upper level while the elevator stop is in action, which will result 60 in the improper presentation of the matrix line to the mold and hence produce a "squirt," or cause damage to the parts, or both.

The present invention is intended to overcome the above objection and aims to prevent the delivery of the matrix line to the mold except under the proper conditions. To this end, the machine is equipped with a safety device which acts when the elevator stop is in active position to prevent the 70 transfer of the matrix line into the elevator, unless such line is composed at the lower level. In the embodiment herein illustrated, the stop is in the form of a pivoted lever carried by the first elevator and movable to 75 active or inactive position thereon, and the safety device is in the form of a rod connected at one end to the pivoted lever and having its other end arranged to be moved into and out of the first elevator at its entrance, 80 the arrangement being such that when the stop is moved to active and inactive position, the rod will be projected into and withdrawn from the first elevator respectively, thereby preventing or permitting the transfer into 85 said elevator of matrices standing at the upper level, according to the position of the elevator stop.

In the accompanying drawing, the present embodiment is shown merely by way of 90 example and in preferred form and as applied to the specific kind of machine mentioned, but obviously many changes and variations may be made therein without departing from the spirit of the invention, 95 which, it is therefore to be understood, is not limited to any specific form or embodiment except in so far as such limitations are specified in the claims.

Referring to the drawing:

Figure 1 is a front elevation of a portion of a linotype machine having the present improvements applied thereto:

Fig. 2 is a vertical section taken through the casting mechanism, and showing the first 105 elevator in raised position preparatory to the engagement of the mold with the matrix line for the casting operation; and

Fig. 3 is a top plan view of the parts shown in Fig. 2.

The matrices X (herein shown as of the two-letter variety) are stored in the magazine A and are released therefrom in the usual way by the manipulation of the keyboard B, whence they pass into the assembling elevator C wherein they are composed in line. After composition of the line, the elevator C is raised into registration with the intermediate channel D, such movement 10 of the elevator tripping the transfer carriage E, which thereupon shifts the composed line to the left into the first elevator or transporter F. The first elevator then descends to locate the line before the casting mold G, which immediately advances from the rear into engagement therewith preparatory to the casting operation, all as well understood in the art. As before indicated, the assembling elevator C, the intermediate channel D, and the first elevator F are each provided with two sets of supporting rails, for sustaining the matrices at the upper or lower level, as required. This construction is so well known that no detailed description 25 thereof seems necessary, but, to identify the parts, it may be noted that the matrices are sustained at the upper level in the assembling elevator C by the retractable rails C¹ and C² (Fig. 1) and in the first elevator F by the retractable blade or rail F¹ (Fig. 2), which latter figure also shows the fixed rails F² for sustaining the matrices at the lower level in the first elevator. It may also be noted that the mold G is formed 30 at the front with the two superposed grooves G¹ and G², in one or the other of which the alining ears of matrices engage according to the level at which they are sustained in the first elevator. If a fuller understanding of the construction and operation of these parts is desired, reference may be had 35 to the Rogers Re. Patent No. 13,489.

In the normal operation of the machine, the first elevator F is allowed to descend to 40 its lowermost position, as determined by the engagement of its set screw F³ with the top face of the vise frame H. In this connection, it is pointed out that the elevator is provided with a second set screw F⁴ arranged 45 to engage and depress the "vise automatic" H¹ as the elevator comes to rest. However, for reasons previously noted, the machine is usually equipped with a stop member which may be thrown into action 50 at will to arrest the first elevator in a raised position with reference to the mold, as shown in Fig. 2, but when the elevator is thus arrested, it is necessary that the matrices be sustained therein at the lower level, as 55 otherwise the objections before mentioned will arise. Thus, if the matrices were sustained at the upper level, as indicated by the dotted lines in Fig. 2, it is evident that their lower ears would fail to enter the 60 upper alining groove G¹ of the mold G as

the latter advances from the rear, so that injury to the parts or a bad "squirt" would necessarily result.

According to the present invention, and to obviate the foregoing objection, means 70 are provided to prevent the entrance of the composed line into the first elevator at the upper level when the elevator is to be arrested in its raised position. To accomplish this result, specifically, the stop member for 75 the first elevator is mounted directly thereon, and the elevator is further equipped with a device connected to the elevator stop and which is arranged to be projected into and out of the elevator as the stop member is 80 moved to active and inactive position, respectively. In the preferred embodiment illustrated, the elevator stop is in the form of a horizontally disposed angular lever O pivoted to the under side of the elevator 85 head by a screw-bolt or pin O¹ and provided on its two arms with interponents O² and O³, respectively, the former being arranged to coöperate with the set-screw F³ which limits the descent of the elevator, and 90 the latter being arranged to coöperate with the set-screw F⁴ which actuates the "vise automatic" H¹. The longer arm of the pivoted lever projects to the right beyond the elevator head (Fig. 3) so as to provide 95 a handle portion within easy reach of the operator while seated at the keyboard, and stop pins O⁴ and O⁵ serve to limit the movement of the lever in opposite directions. The pin O⁴ is arranged to arrest the lever 100 in its active position i. e. with the interponents O² and O³ beneath their respective set-screws F³ and F⁴ as shown by the full lines in Fig. 3, while the pin O⁵ is arranged 105 to arrest the lever in its inactive position i. e. with the interponents located clear of the set screws as shown by the dotted lines in said figure. It is apparent, that by adjusting the stop lever to active or inactive position, the first elevator will be arrested 110 in raised relation to the mold (Fig. 2), or allowed to occupy its normal relation thereto, according to the adjustment of the stop lever.

Referring now to the safety device, it is 115 merely in the form of a small rod P connected at one end to the handle portion of the stop lever O and having its opposite end slidably arranged in a hole or opening cut through the front wall of the first elevator at its entrance and at a point located 120 above the fixed matrix supporting rails F², the length of the rod being such that it will be projected into and withdrawn from the elevator as the stop lever is moved to active 125 and inactive position respectively. Consequently, if the matrix line should be improperly composed at the upper level while the elevator stop is in action, the rod P will 130 bar the entrance to the first elevator chan-

nel (Figs. 2 and 3) and thus prevent the transfer of the matrix line thereinto, so that no damage can result. If, however, the line has been properly composed at the lower 5 level, it may be transferred into the first elevator notwithstanding the fact that the rod is in its arresting position. In other words, the arrangement is such that when the parts are adjusted to arrest the first 10 elevator in its raised position, the matrices must be assembled at their lower level before they can be transferred into the first elevator for the type casting operation. It will be understood, of course, that when the elevator 15 stop is out of action, the matrices may be composed at the upper or lower level or both, as the elevator in such condition of the stop is permitted to descend to its normal position.

20 It is particularly noted that, in the foregoing arrangement, the parts are extremely simple and can be made at small cost and applied to the machine without the slightest difficulty or delay, and this without involving any radical alteration in the existing 25 machine parts. In addition, the arrangement is strong, durable and compact and such that it may be easily and conveniently manipulated. The form and arrangement 30 of the elevator stop as above described is also very advantageous, quite apart from its association with the safety device, it being remembered that the stop lever is carried by the first elevator and is provided with a 35 handle portion projecting beyond the same toward the right within easy reach of the operator while seated at the keyboard. These and other advantages will be apparent to those skilled in the art. However, in 40 its broader aspects, the invention is not limited to the precise construction shown and described, as many changes may be made in the details thereof and still be comprised within its scope. Generally speaking, it is 45 to be understood that the invention is not limited to any specific form or embodiment except in so far as such limitations are specified in the claims.

Having thus described my invention, its 50 construction and mode of operation, what I claim is as follows:

1. In a typographical casting machine, the combination of a mold, a transporter movable into and out of operative relation therewith and constructed to support matrices therein at different levels, adjustable means carried by the transporter to vary the vertical position thereof in reference to the mold, and a device controlled by said means to 55 permit or prevent the support of matrices at an upper level within the transporter according to the adjustment of said means.

2. In a typographical casting machine, the combination of a mold, a transporter mov-

able into and out of operative relation therewith and constructed to support matrices therein at different levels, adjustable means carried by the transporter to vary the vertical position thereof in reference to the mold, and a device controlled by said adjustable 65 means to permit or prevent the entrance of matrices into the transporter at an upper level, according to the adjustment of said means.

3. In a typographical casting machine, the combination of a mold, a transporter movable into and out of operative relation therewith and constructed to support matrices therein at different levels, adjustable means carried by the transporter to vary the vertical position thereof in reference to the mold, and a device also carried by the transporter and controlled by said adjustable means to 70 permit or prevent the entrance of matrices into said transporter at an upper level according to the adjustment of said means.

4. In a linotype machine, the combination with the assembling elevator, the intermediate channel, and the first elevator, each constructed to sustain matrices at different levels therein, and the transfer carriage for shifting the composed line from the assembling elevator through the intermediate channel into the first elevator, of a stop member carried by the first elevator and 75 adjustable to active or inactive position thereon so as to arrest said elevator in raised position or permit it to descend to its normal position, and a device controlled by the stop member and arranged to be projected 80 into or withdrawn from the path of matrices standing at an upper level according to the adjustment of said stop member.

5. In a linotype machine, the combination of the vertically movable first elevator constructed to support matrices at different levels therein, a stop member carried by the elevator and movable thereon to active or inactive position, and a safety device also carried by the elevator and connected to the 85 stop member, said safety device being arranged to be projected into and withdrawn 90 from the elevator at its entrance as said stop member is moved to active and inactive position, respectively, for the purpose described.

6. In a linotype machine, the combination of the first elevator constructed to support matrices at different levels therein, the pivoted stop lever O carried by the first elevator, and the safety rod P also carried by the elevator and connected to the pivoted lever, the said parts being arranged substantially as shown and described.

In testimony whereof, I have affixed my 125 signature hereto.

LUTHER SHERRILL.
